Term of patent 14 years

Int. Cl. D25—01

U.S. Cl. D13—1 H

FIG. 1 is a side elevational view of the truss embodying the invention.

FIG. 2 is an end view of the same.

FIG. 3 is a fragmentary side elevational view of the same on an enlarged scale.

FIG. 4 is a fragmentary plan view of the same.

FIG. 5 is a sectional view taken along the line 5-5 in FIG. 3.

FIG. 6 is a sectional view taken along the line 6-6 in FIG. 3.

The design is characterized by angularly related legs each of which is U-shaped in cross section having a base

that increases in width from the center to the ends and walls which decrease in width from the center to the ends, which walls have curved free edges.

What I claim is:

The ornamental design for a truss, as shown and described.
